UNITED STATES PATENT OFFICE.

NICOLAS JAPOLSKY, OF LONDON, ENGLAND.

ELECTROMAGNETIC TOOL.

Application filed January 18, 1925. Serial No. 2,197.

To all whom it may concern:

Be it known that I, NICOLAS JAPOLSKY, a citizen of Russia, and residing at 68a, Lincoln's Inn Fields, London, W. C. 2, Eng-

5 land, have invented a certain new and useful Improved Electromagnetic Tool, of which the following is a specification.

This invention relates to electromagnetic tools of the kind in which the active member 10 is reciprocated.

The object of the invention is to provide an improved construction of electromagnetic hammer, borer or the like reciprocating tool.

The invention consists in electromagnetic 15 tools of the kind in which the active member reciprocates characterized in that the said reciprocating member is an electric conductor which is arranged in the air gap of a magnetic circuit of constant polarity 20 and is traversed by an alternating current, the action of which on the field in the air gap produces the reciprocation of the said member.

The invention also consists in the further 25 features as hereinafter described and claimed.

Reference will now be made to the accompanying diagrammatic views which illustrate by way of examples different forms of 30 electromagnetic devices according to the invention.

In these drawings:—

Figure 1 shows diagrammatically one construction of reciprocating tool.

35 Figure 2 is a modification of the arrangement according to Figure 1.

Figure 3 shows another form of construction.

Figure 4 shows a detail of same.

40 Figures 5 and 6 are modifications of the foregoing.

Figures 7, 8, 9 and 10 show three further diagrammatic arrangements.

45 Figures 11 and 12 show a sixth constructive arrangement and

Figures 13 and 14 show a seventh arrangement.

In the diagram, Figure 1, the tool comprises an electromagnet A, which is fed by 50 a continuous electric current by means of the terminals 1 and 2. B is the active member which is made of electric conducting material and is adapted to reciprocate, being connected by flexible conductors 5 and 6 to 55 terminals 3 and 4 of the secondary winding of an alternating current transformer T.

C represents a small impact member that is intended to perform the work of the tool and is acted upon by the reciprocative member B.

60 The electromagnet A produces a constant magnetic field with poles N and S, in the air gap of which the active member B is situated. The member B is traversed by an alternating current, the action of which upon the magnetic field causes the displacement of the member B in a reciprocating manner in order to actuate the impact member C.

65 In the modification according to Figure 2 the flexible conductors 5 and 6 are dispensed with and are replaced by fixed guides D, each of which is connected to one of the terminals 3 and 4 of the secondary winding 70 of the transformer T.

75 The active member B is adapted to move in the guides D with which it makes good conductive contact.

80 Referring to Figures 3 and 4 these illustrate a constructive arrangement in which the active member B itself constitutes the secondary of a transformer T, the core T' and the closed magnetic circuit of which are fixed. As in the previous example the reciprocative member B is traversed by an 85 alternating current, the action of which upon the magnetic field produced in the gap between the poles N and S causes the reciprocating movement of the member B which in turn transmits its energy to the 90 impact member C. The member B seen in plan in Figure 4 is provided with a central opening B² through which is linked the magnetic core of the transformer T.

95 In a modification of the above arrangement and shown in Figure 5 the member B comprises a fixed portion B' that is provided with two guides B². In these guides is adapted to slide the movable part B³ which at the same time remains in good electrical 100 contact therewith.

105 The movable part B³ being traversed by an alternating current, its action upon the constant magnetic field causes the reciprocating displacement of the part B³.

In the arrangement shown in Figure 6 the member B is fixed and is connected to the movable portion B' by the flexible conductors B².

110 The arrangement according to Figure 7 differs from the preceding forms in that the part B is subjected to the action of two con-

stant magnetic fields produced the one by the electromagnet A and the other by the electromagnet A¹.

T' is the core of the transformer T which is looped with the member B, while C represents the impact member.

In the modification shown in Figure 8 the windings that produce the constant magnetic field and the primary winding of the transformer having an alternating current T are arranged on a common magnetic core A. For this purpose a continuous current led to the terminals 1 and 2 traverses the four windings I, II, I' and II₁ which are arranged in such a manner that their magnetic fluxes follow the courses indicated by the dotted lines b. With regard to the alternating currents these are led from the terminals 3 and 4 and traverse the two primary windings III, IV, the magnetic fluxes of which, in the same direction follow the course of least resistance, that is to say the course a. The secondary of the transformer, as in the preceding case, is formed by the active part B which has in plan the shape illustrated in Figure 9. The continuous current circuit could comprise two more windings arranged on the polar parts N and S, in such a way as to increase the flux traversing the same.

The further modification shown in Figure 10 is similar to that shown in Figures 8 and 9, but in this case the active member B is arranged in a plane perpendicular to the direction of its movement; moreover the impact member C traverses a hole provided in the core A while the member B works on this core by means of the opening B¹, which is provided in the centre part of the main core A.

In the arrangement according to Figures 11 and 12, the magnetic core A of the transformer is provided with a central branch A₁ along which the active member B can be displaced. The member B is seen in

front view in Figure 12. The continuous current windings I and II are arranged on the central branch A₁ in such a manner that their fluxes b have opposite directions in the same; the alternating current windings III and IV are also arranged on the branch A₁, but in such a manner that their fluxes assist one another.

In the arrangement according to Figures 13 and 14 A represents a magnetic cylinder which is provided with a central longitudinal branch A₁. At each extremity of this branch is arranged a continuous current winding I, II respectively, the fluxes b of which are directed in opposite directions in the branch A₁. Along the latter is displaceable the active member B which is constituted by an electric winding connected by the flexible connections B₁ to a source of alternating current not illustrated. The interior of the branch A₁ is hollow and contains a guide C₁ intended to act on the impact member C. This guide is connected to the movable member B by the cross member B⁰ that moves in the slits in the branch A₁.

Having now described my invention, what I claim as new and desire to secure by Letters Patent is:—

1. An electromagnetic tool comprising in combination an electromagnet of constant polarity having an air gap, a reciprocative member which is an electric conductor, arranged in the air gap, and means for supplying alternating current to said member to cause in the air gap its reciprocation.

2. An electromagnetic tool as claimed in claim 1, in combination with a transformer the core and the primary winding of which are fixed, the reciprocating member constituting, in part at least, the secondary winding.

In testimony whereof I have signed my name to this specification.

NICOLAS JAPOLSKY.
